HENRY HISE, OF OTTAWA, ILLINOIS.

Letters Patent No. 60,891, dated January 1, 1867.

IMPROVEMENT IN CONDUCTORS' TICKET BOXES.

The Schedule referred to in these Letters Patent and making part of the same.

TO ALL WHOM IT MAY CONCERN:

Be it known that I, HENRY HISE, of the city of Ottawa, county of La Salle, in the State of Illinois, have invented a new and improved "Check Box" for Railroad or other Conductors; and I do hereby declare that the following is a full and exact description thereof, reference being had to the accompanying drawings, and to the letters of reference marked thereon, in which like parts are indicated by like letters in the several figures.

The nature of my invention consists in so constructing a box (or boxes,) in which tickets are deposited, that a conductor will not be able to appropriate to himself "way fares," without a certainty of detection, thus being in other words a "tell-tale" invention.

To enable others skilled in the art to make and use my invention, I will proceed to describe its construction and operation. In the drawings—

Figure 1 represents a central longitudinal section of my ticket box.

Figure 2, a top view of same.

Figure 3, a section of my deposit box.

Figure 4, a plan of the ticket used.

It seems to be a patent fact, that on railroads, it is often the case that way fares are appropriated by conductors, as a kind of "perquisite," although it is not intended they should do so.

The object of my invention is to prevent such appropriation of way fares. To this end, before a train starts, the ticket clerk puts into the hands of a conductor, a box, A, containing a lot of tickets, B. This box has a lid, C, with openings *a* *b* and *c* in it, and only partially covering the top of box A, and about half of the tickets B. This lid is turned down, having a kind of lip, *d*, which takes under another lip, *e*, on the top of partitions *k*. At the other end it has a projection, *f*, turning down over the end *a'* of box A. This box, A, has a circular projection, *g*, say three-fourths of a circle. The part *f* of the lid C, which turns down over the end *a'* of A, has also a curved projection, *h*, say one-fourth of a circle, completing that of *g*. Part of *f* extends below this, as seen at *f'*. The recess made by *g* and *h* is intended to be filled with some kind of sealing wax, to be appropriately stamped for safety, from removal or violation, without detection. This will be seen illustrated by the deposit box, fig. 3, the lid of which is secured in a similar manner. In fig. 1, the red lines A' represent a removable lid. This there is no obstacle to removing at any time a ticket may be wanted for a way passenger, and when removed, half of the ticket can be torn off and given to a passenger after filling up the price or amount of fare, as also marking on the same the station where the passenger got on and where he is to get off. These data are also put on the other half of the ticket, through the holes *a* and *c* of lid C, and that half of the ticket must be pushed aside by the conductor into the chamber, D, to facilitate which, as also assist in tearing the ticket into two parts, the slot *i* is made. Slots *j* *j'*, (through which partition guides *k* pass,) also assist in holding the ticket in place, prevent its entire abstraction, and weaken it for tearing. The tickets should be regularly numbered, 1, 2, 3, 4, &c. It will be seen that the conductor must push the half ticket he retains out of the way in the direction of arrow *z*, before he can fill up the next one under it. He cannot easily abstract it. Beside this box, I use an accessory one, E, having a drop hole, *l*, in the top or side. This box is intended to be hung at some convenient place in the car, say near the door, and into which it is intended way passengers shall drop their tickets before leaving, or as they leave the car, or the conductor may take it "around," when collecting tickets, and let the "way passengers" drop their tickets into it. This, however, may not be desirable. On the contrary, when left at the door, he will not know who deposit their tickets and who do not. This ignorance is the best guard from his abstracting any of the duplicates from box A, even if it be practicable. At the end of the route, the two sealed boxes, A and E, are handed to the ticket agent, who breaks the seals and compares the contents of each. If there be a half ticket in E which is not in chamber D, the inference (or certainty) is, the conductor has appropriated that way fare. In the chamber, F, of box A, there is a spring, *m*, extending nearly its whole length, and passing between the two partitions, *k*, which pass between the lateral slots *j* *j'* of ticket B. This spring supports a plate or platform, *N*, upon which rest the tickets, and this spring keeps them pressed up against the lid C of the box A. The box E performs a very important part in the invention or proposed safety guard, as well as in the detection of any fraud. Besides insuring a return of the half tickets left in apartment D of box A, it also prevents marking the fare on tickets

lower than the fixed rates, for those in each box should correspond, and the passenger who drops his ticket into box E can see if the conductor has marked on it the price or fare paid him. There should be one of these boxes at each car door. As to box E co-operating with box A as a detective, any suitable attachment may be made around drop hole *l* to prevent any abstraction of the passengers' tickets I have indicated an arrangement—a box with four sides, having a spring at the bottom, (see red ink lines.)

Having thus described my invention, what I claim as new, and desire to secure by Letters Patent of the

United States, is—

1. The box A, provided with the apartment F, spring *m*, lid C, and chamber D, arranged and combined and operating in the manner shown and described and for the purpose set forth.
2. The secondary box E, when used in connection with box A, and constructed of the two parts as described, box proper and lid, the latter provided with a slot *l*, and lip *f'*, as shown and described and for the purpose set forth.
3. The tickets B, having the slots *i* *j* and *j'*, for the purpose set forth.
4. The combination of tickets B with box A, constructed and arranged as described.
5. As a complete method of detection, or as a safety guard, I claim the combination of box A, tickets B, and deposit box E, constructed, arranged, and operating substantially in the manner described, and for the purpose set forth.

HENRY HISE.
